METHOD OF COKING PETROLEUM
RESIDUES OR THE LIKEMalcolm H. Tuttle, New Rochelle, N. Y., assignor
to Max B. Miller & Co., Inc., New York, N. Y., a
corporation of Delaware

Application May 22, 1941, Serial No. 394,658

11 Claims. (Cl. 202—14)

This invention relates to a method of coking petroleum residues and the like.

In the refining of petroleum, it has long been common practice to top off the readily volatile constituents of the crude and then crack the residue by heat, usually under pressure. If the cracking is continued to the extent necessary to produce the desired high yields, there is deposited on the walls of the stills a hard tenacious crust. This crust builds up in thickness until it becomes necessary to interrupt the cracking operations and remove the crust from the walls of the stills. This is a troublesome and expensive operation. If the cracking is not continued to the end-point, an uncracked residuum, commonly referred to as pressure tar, is left as a waste product.

It has heretofore been proposed to coke tarry materials by spraying them onto a stationary bed of coke heated from below. This process has the disadvantage, among others, that the coking operations must be interrupted from time to time in order to remove the coke from the floor of the still.

It has also been proposed to preheat the coke and feed it through a zone where petroleum is sprayed onto it. Some of the proposals to this effect are unfeasible because the mass becomes gummy and sticks to the apparatus; others are impractical because the apparatus is expensive to build and inefficient in operation.

The present invention provides a novel method of separating petroleum residue or the like into volatile constituents and coke while avoiding the aforementioned disadvantages. According to my invention, a bed of hot granular material is rabbled and the petroleum residue is fed onto the surface of the loose, rabbled material. In the preferred mode of practising my invention, the bed is rabbled to a depth greater than the depth to which wet petroleum penetrates and the wet tar on each portion of the bed is permitted to become substantially dry or non-sticky before that portion of the bed is again rabbled. The tar is thus always deposited on hot loose material and is coked before any wet tar reaches the bottom of the bed; and the particles of the material on which the tar is deposited are prevented from sticking to each other or to the walls and other parts of the apparatus. My invention enables continuously feeding the petroleum residue and continuously withdrawing loose coke-coated material. Petroleum residues can thus be converted into vapors and coke or gases without leaving a hard crust on the apparatus.

According to one form of my invention the

granular material is preheated and is then dropped into a coking chamber. The coking takes place by transfer of the heat from the granular material to the petroleum residue or the like. 5 However, my present invention can be practiced in connection with other coking methods which involve different ways of supplying heat to material to be coked. Although such other methods are illustrated in Figs. 2, 3 and 4 of the accompanying drawings with a view to indicating certain applications of the invention claimed herein, they involve separate and distinct inventions claimed in my copending applications, Serial No. 396,020, filed May 31, 1941, and Serial No. 401,701, filed July 10, 1940, to which reference is made for further details.

Other features, objects and advantages of the invention will in part be pointed out and in part become apparent in connection with the following detailed description of methods according to the invention, references being had to the accompanying drawings wherein:

Fig. 1 is a vertical section through one form of apparatus suitable for carrying out the method according to the invention; and

Figs. 2, 3 and 4 are similar views through other forms of apparatus in which the present invention can be practised.

In Fig. 1 there is shown at 10 a cylindrical still which includes a number of shelves 11 having openings 12 and 13 disposed alternately near the center and near the outside wall of the still. In the center there is a rotating housing 14 which may be driven from any suitable motor 21 through gearing 22, 23 and which carries a pipe 15 connected to horizontal tubular arms 16. Petroleum residue or the like is supplied through a pipe 18 connected to the pipe 15 by a suitable coupling 17. The arms 16 have teeth 20 which extend into the granular material on the hearths for rabbled or raking this material as the arms rotate. The arms 16 are provided with openings or ports 19 in their rear sides. That is to say, the ports 19 are arranged so that they spray the tar in back of the teeth 20 and onto portions of the bed which has just been rabbled. In this way, all the petroleum residue strikes freshly rabbled portions of the bed. The speed of rotation of the arms 16 and the rate of feed of the petroleum residue are adjusted so that the latter becomes substantially dry before the surface is again rabbled. Moreover, the thickness of the bed is such that the tar is separated into vapors and coke before wet tar reaches the bottom of

the bed. If desired, the arms 16 could be held stationary and the shelves 11 could be rotated.

Preheated granular material 24 is fed onto the top shelf through an opening 25. It is gradually advanced onto the next shelf under the action of the rabble arms. The granular material is fed into the apparatus at a temperature above the coking temperature, for instance at about 1000° to 1400° F. The petroleum residue to be coked is fed continuously through the tubular arms 18. When the petroleum residue strikes the granular material at such temperature heat is transferred to it and it is converted into vapors and coke. I prefer to control the rate of introduction of the granular material so that there is always a bed of granular material of substantial thickness on the hearths of the furnace. By agitating successive portions of the granular material on which the petroleum residue is sprayed to at least the depth of penetration of the petroleum, binding together of the particles is avoided, the coke forms on the separate particles, and the tar does not stick to the hearths. The depth to which the teeth of the rabble arms penetrate the bed of granular material may be arranged to suit particular rates of feed, but the rabbling teeth should penetrate the bed to such an extent that the raking action prevents agglomeration of the particles. It will be appreciated that the depth of the bed of granular material of each of the shelves, the number of shelves employed, and the rates of feed of the petroleum residue and granular material can be readily controlled to make the best use of the available heat according to heat-balance calculations.

The granular material covered with coke formed in the apparatus is continuously discharged along the inclined passage 26. The hydrocarbon vapors formed are withdrawn through a pipe 38 into a condenser 39 and thence into a receiver 40.

The granular material which is used in accordance with the invention may be an incombustible substance such as ground bauxite or it may be coke or carbon. It will be understood, however, that other granular materials may be employed in place of those specifically mentioned. It is preferable to employ a substance which is somewhat absorbent and which is not melted by the heat employed in the process. I have found that when using bauxite as the granular material, the particles coated with coke are readily discharged from the apparatus even though they contain as much as 28% by weight of uncoked tarry material which can be extracted from the product by solvents for petroleum such as naphtha. However, the process can be run to the end-point so that the coke produced is substantially free from such extractable constituents. When coke is used as the granular material the product may thus consist of practically pure carbon which is adapted for use as metallurgical coke.

When the term "granular material" is used herein, it means hard grains but does not mean that these grains must be very small. Ordinary pea sized particles work very well, but particles as small as 30-60 mesh may be used. Excessively large lumps are not preferred inasmuch as they do not present as much surface to the liquid as do relatively small grains.

In Fig. 2 there is shown a retort 50 which is divided by metal partition 51 into a heating compartment 52 and a coking compartment 53. Burners 54 supply heat to the top of the partition.

The products of combustion escape around baffle 55 through a stack 56. A bed of granular coke 57 is maintained in the bottom of the retort. Additional coke may be fed through the opening 53 as desired. A rotating rabble arm 58 is provided with fingers 60 and with openings 61 for the purposes described in connection with Fig. 1. Petroleum to be coked is fed through line 62 to the arm 59 which is driven through a shaft 63, 10 a pulley 70 and a belt 71. The vapors produced are withdrawn through a pipe 72 and the coke produced is withdrawn through the inclined passage 73.

In Fig. 3 there is shown a somewhat less advantageous application of my present invention. In this form the coking is conducted in a chamber 75, the heat being supplied to the bed of granular material 76 by burners 77 located beneath the chamber. The rotating rabble arm 58 15 is constructed and operated the same as described in connection with Figs. 1 and 2 except that the drive shaft extends up through the top of the apparatus instead of down through the bottom. Passages 58, 72 and 73 are provided for the same purposes as mentioned in connection with Fig. 2.

In Fig. 4 there is shown diagrammatically another form of apparatus in which my present invention may be used. This apparatus includes 30 a metal shell 80 in which there is a chamber 81 which is heat-insulated by a refractory lining 82 and an asbestos outer jacket 83. A deep bed of granular coke 84 is maintained in the chamber 81. Air for supporting combustion in the bottom of the coke bed is introduced through a pipe 85. A valve 86 is provided for withdrawing coke or non-combustible material. A rotating rabble arm 87 on shaft 88 is constructed the same and operates the same as described in connection 35 with Figs. 1, 2 and 3. The petroleum is coked by the heat which rises through the upper portions of the bed 84. A passage 89 leads into the chamber 81 above the rabble arm for withdrawing the vapors produced. If desired, a screw 40 conveyor 90 may be provided for withdrawing coke formed by the petroleum which is fed into the top of the bed of coke.

In accordance with the invention petroleum residues or tars can be heated and distilled so 45 that they are completely converted into vapors and coke. This is feasible even when the material treated is a low grade pressure tar. The granular material on which the coke is deposited, even though the coke contains substantial amounts of constituents which can be extracted 50 from the coke by solvents, is in such condition, when produced according to the invention, that it is readily discharged from the furnace without tending to stick to the hearths or walls thereof. These coke-coated particles thus produced are well adapted to be burned for reuse in the coking operation.

The present invention has been described in connection with the treatment of petroleum residues, but it may be applied to the coking of other tarry materials such as, for example, coal tars, pressure tars, tars from the Duo Sol or other solvent extraction processes, and the like, which are adapted to be separated or decomposed by heat into coke and vapors. Indeed, it is particularly adapted for treating low grade tars whatever their source. If these materials are highly viscous or normally solid they may be preheated to suitable temperature below the coking temperature, for instance, to about 700°-800° F. For

simplicity, the term "tar" as used in the claims includes such materials whether obtained from petroleum or from other sources.

The terms and expressions which have been employed are used as terms of description and not of limitation, and there is no intention, in the use of such terms and expressions, of excluding any equivalents of the features shown and described, or portions thereof, but it is recognized that various modifications are possible within the scope of the following claims.

What I claim is:

1. Method of coking tar which comprises maintaining a bed of hot granular material, intermittently rabbling the bed and applying tar thereto, and permitting each application of tar to coke to substantial dryness before again rabbling the bed.

2. Method of coking tar which comprises intermittently feeding tar to a bed of hot granular material so that it does not penetrate to the bottom of the bed and rabbling the upper portion of the bed to the depth to which the tar penetrates, and permitting each application of tar to coke to substantial dryness before again rabbling the bed.

3. Method of coking tar which comprises maintaining a bed of hot granular material, feeding tar to certain portions of the bed while rabbling the other portions, feeding tar to other portions of the bed while rabbling the first-named portions and permitting the tar applied to each portion of the bed to coke to substantial dryness before thereafter rabbling that portion of the bed.

4. The method as claimed in claim 3 wherein tar is continuously fed to the bed and coke and vapors are continuously withdrawn.

5. The method as claimed in claim 3 wherein the bed is circular and the tar is distributed along a continually rotating radius.

6. Method of coking tar which comprises continually feeding granular material onto a supporting surface, continual application of tar to said material at certain timed intervals measured with respect to the rate of tar carbonization, continually rabbling portions of said material during intervals when the tar on said

portions of the material is non-sticky, and continually removing the coke and vapors formed.

7. Method of coking tar, which comprises maintaining a bed of hot granular material of sufficient depth to separate the tar into vapors and coke before wet tar reaches the bottom of the bed, rabbling the bed to a depth as great as that to which tar penetrates into the bed, distributing tar onto the surface of the rabbled bed, and permitting the tar to become substantially dry before again rabbling the surface.

8. Method of coking tar, which comprises maintaining a uniform bed of preheated granular material which is sufficiently hot and sufficiently deep to separate tar into vapors and coke before wet tar reaches the bottom of the bed, rabbling the upper portion of the bed, continuously distributing fluid tar onto non-sticky, rabbled portions of the surface of said bed, and allowing time for the tar to separate into vapors and coke before again rabbling that portion of the surface of the bed to which tar has been applied.

9. Method of coking tar which comprises distributing tar onto a hot, freshly rabbled, quiescent bed of granular material, permitting the tar to decompose to a point where it is non-sticky, and then rabbling the granular material on which the tar has been coked before again feeding tar to this portion of the bed.

10. Method of coking tar which comprises distributing tar onto a portion of the surface of a bed of hot granular material, permitting the tar to become converted to coke and vapors, thereafter moving some particles in said portion of the bed with respect to other particles to prevent bonding between particles, and thereafter distributing more tar onto the same portion of the surface of the bed.

11. The method of coking tar which comprises preheating granular material, feeding the pre-heated granular material onto a bed of said material on a stationary support, feeding tar onto the surface of the bed, allowing the tar to coke, thereafter rabbling the bed, and continuously withdrawing coke-coated granular material and vapors.

MALCOLM H. TUTTLE.

CERTIFICATE OF CORRECTION.

Patent No. 2,314,112.

March 16, 1943.

MALCOLM H. TUTTLE.

It is hereby certified that error appears in the printed specification of the above numbered patent requiring correction as follows: Page 1, second column, line 15, for "July 10, 1940" read --July 10, 1941--; and that the said Letters Patent should be read with this correction therein that the same may conform to the record of the case in the Patent Office.

Signed and sealed this 18th day of May, A. D. 1943.

Henry. Van Arsdale,
Acting Commissioner of Patents.
